UNITED STATES PATENT OFFICE.

JOSHUA W. TRUSSELL, OF ROCKLAND, MAINE, ASSIGNOR TO JOSEPH W. COVEL AND JOHN E. HANLY, BOTH OF SAME PLACE.

DOOR-SECURER.

SPECIFICATION forming part of Letters Patent No. 244,951, dated July 26, 1881.

Application filed April 9, 1881. (Model.)

To all whom it may concern:

Be it known that I, JOSHUA WATSON TRUSSELL, of Rockland, in the county of Knox and State of Maine, have invented a new and useful Improvement in Safety-Keys for Door-Fastenings; and I do hereby declare that the following is a full, clear, and exact description of the same.

My invention relates to improvements in safety-keys for fastening doors, drawers, cases, or where locks are ordinarily used, in which a central shaft armed with sharp projections from two opposite sides is inclosed in a rectangular wedge-shaped frame, the shaft being provided with a thumb-screw head in one instance and a lever in the other, for turning it at right angles with the frame; and the objects of my improvement are, first, simplicity of structure; second, to make easy and quick adjustment; third, in being totally out of reach from the opposite side of the door; fourth, in being adjustable to any kind of door. I attain these objects by the special construction hereinafter set forth, and the accompanying drawings, in which—

Figure 1 represents a side view; Fig. 2, an end view. Fig. 3 shows central shaft turned down as in use for top and bottom of door from the outside.

In the accompanying drawings similar letters refer to similar parts.

Fig. 1 represents a side view, in which *a* is the thumb-screw handle; *d*, the central shaft; *b*, the rectangular wedge-shaped frame, and *c* the sharp projections from two opposite sides of the shaft. The shape of the frame *b* is seen to be wedge-shaped, thus admitting of use on tight-fitting doors, also to force the door away from the frame on that side, preventing any

loose motion. The frame also protects the 40 pocket from the sharp projections.

As shown in Fig. 2, the safety-key is forced between the closed door and its frame until held firmly in place. The central shaft is then turned by means of the thumb-screw handle 45 *a* at right angles to the frame *b*, thus causing the projection *c* to enter the wood-work on either side and firmly binding them together. The frame *b* is hinged to the central shaft, *d*, by a stout pivot, *f*. The end of the central shaft, 50 *d*, being square, admits of purchase in turning the shaft when bent at right angles. This is the shape of the safety-key, Fig. 3, ready for use at bottom of the door. Inserted flat-wise beneath the door, and forced in as far as 55 possible, the shaft is then turned at right angles by means of the lever made of the frame *b*.

I am aware that door-securers in the form of wedge-shaped shafts armed with opposite sharp projections are not broadly new. I do not therefore claim such a securer; but

What I do claim is—

In a door-securer, the combination, with the shaft *a*, armed with opposite sharp projections, of the frame *b*, in which said shaft is journaled, having beveled faces, substantially as described, whereby the said projections are compelled to sink equally deep in the wood of both door and jamb, and whereby the strength of the fastening is increased.

In testimony whereof I have signed my name to this specification in the presence of two subscribing witnesses.

JOSHUA WATSON TRUSSELL.
